UNITED STATES PATENT OFFICE.

FLORENCE WILLIAM HOOS AND EMIL MANN, OF PHILADELPHIA, PENNSYLVANIA.

ICE-MACHINE.

SPECIFICATION forming part of Letters Patent No. 469,999, dated March 1, 1892.

Application filed October 17, 1891. Serial No. 409,012. (No model.)

To all whom it may concern:

Be it known that we, FLORENCE WILLIAM HOOS and EMIL MANN, citizens of the United States, both residing in the city and county of Philadelphia, State of Pennsylvania, have invented a new and useful Improvement in Ice-Machines, which improvement is fully set forth in the following specification and accompanying drawings.

10 Our invention relates to improvements in ice-machines; and it consists of means, substantially as described, for automatically feeding the still thereof from an overflow-tank.

It further consists of the combination of 15 parts hereinafter set forth.

Figure 1 represents a side view of an ice-machine embodying our invention. Fig. 2 represents a sectional view on line xx , Fig. 1.

Similar letters of reference indicate corresponding parts in the two figures.

Referring to the drawings, A designates a still or boiler having an inlet B therein and an outlet-pipe C with a valve D therein. The pipe C leads from the still A to the anhydrous ammonia receiver E, a portion of said pipe being coiled, forming a condenser D'. A pipe F leads from the said receiver to the expansion-coils G, connected with the pipe H, which passes over the condenser-coils D' to an ab-

30 sorber J. Leading from the lower end of the still A is a pipe L, which has a valve K therein and is provided with the coils L', located below the condenser-coils D', the continuation of the said pipe beyond the coils entering the absorber J at or near the lower end thereof.

An air or vapor pipe M, provided with a valve M', leads from the upper end of the absorber J downwardly and into a water vessel M^x, located on the floor or lower part of the machine.

40 A pipe N connects the upper part of the absorber with an injector P, and a pipe Q leads from said injector to the still A. The pipe N is provided with a valve R, and the pipe Q is provided with a check-valve S and a controlling-valve T, the latter being between the said check-valve and the still.

U designates an overflow-tank directly connected by the pipe V with the absorber J and provided with a pipe W, which communicates 50 with the injector P and is connected by a branch pipe W' with the pipe N. The said

branch W' has a valve X therein, and the pipe W is provided with a valve Y between the branch pipe and the injector.

Z designates a hot-gas pipe leading from 55 the still to the injector, and A' a valve therein.

The operation of the device is as follows: A strong solution of aqua-ammonia is poured into the still A through the inlet B, which is then closed and the still heated until the gage 60 B^x registers a pressure of one hundred and twenty pounds, when the valve D is opened and the ammonia-gas is set free, passing into the pipe C, and thence to the anhydrous-ammonia receiver E through the coils D', which form 65 a condenser for the heated gas therein. From the receiver E the gas then passes through the pipe F into the expansion-coils G, whereby its temperature is greatly reduced, returning by the pipe H over the said condenser-coils 70 D' to the absorber J. At the same time the weak aqua-ammonia in the still A will by the pressure therein, the valve K being open, pass through the pipe L, where it is cooled by the condenser-water, passing then into the absorber J, where it mixes with the gas from the expansion-coils G, thereby forming strong ammonia-water. To set free or expel the air in the apparatus, the valve M' in the pipe M is opened, when the air in the absorber, being 80 under pressure, will escape through said pipe into the water in the vessel M^x, rising by bubbles to the surface thereof, any escaping ammonia gas being absorbed by the water in said vessel. By closing the valves X and 85 A' and opening the valves R and T the feed of the ammonia is directed from the absorber through the injector to the still, the overflow passing from the injector into the pipe W, and so into the overflow-tank. The valve A' 90 of the pipe Z is now opened, and the hot gas from the upper portion of the still passes through the injector, and, mixing with the ammonia, combines with the same as it enters the still through the pipe Q. When the ammonia in the overflow-tank is to be fed to the still, the valve R is closed and the valve X is opened, when the ammonia under pressure in the said tank flows through the pipe W and valve X into the injector, and then through 100 pipe Q into the still, whereupon the valve A' is opened, permitting the hot gas from the

still to escape from the same and mingle with ammonia passing through the injector.

The overflow-tank may receive ammonia directly from the absorber by means of the 5 pipe V, when so desired. It will be seen that the pressure in the overflow-tank is utilized to convey the ammonia in the same to the still without employing a pump.

Having thus described our invention, what 10 we claim as new, and desire to secure by Letters Patent, is—

1. In an ice-machine, an absorber, an overflow-tank, a still, a condenser, pipes leading from said still to said absorber through said 15 condenser, and an injector with pipes leading from said absorber and overflow-tank to said still, said parts being combined substantially as described.

2. In an ice-machine, an absorber, a still, an 20 injector, an overflow-tank, a pipe leading from said absorber to said injector, a valve in said pipe, a pipe leading from said injector to said still, a controlling and a check valve in said

latter pipe, a pipe leading from said injector to said overflow-tank with a valve therein, and 25 a pipe leading from the latter pipe between said latter valve and the tank to the injector, said parts being combined substantially as described.

3. In an ice-machine, an absorber, an overflow-tank, a still, an injector, a pipe leading from said absorber to said injector and having a valve therein, a pipe leading from said injector to said still having controlling and check valves therein, a hot-gas pipe leading 30 from the still to the injector with a valve therein, a pipe leading from the injector to the overflow-tank with a valve therein, and a pipe connecting with said last pipe and leading to the injector having a valve therein, said parts 35 being combined substantially as described.

FLORENCE WILLIAM HOOS.

EMIL MANN.
